**COMBINED GARDEN HOSE ADAPTER AND
RELIEF VALVE**

Jack A. Britton, Lakewood, Ohio

Application September 22, 1955, Serial No. 38,050

Term of patent 14 years

(Cl. D78—1)

Fig. 1 is a side elevational view of a combined garden hose adapter and relief valve showing the design;

Fig. 2 is an elevational view of the left end of the adapter and valve shown in Fig. 1;

Fig. 3 is a top view of the adapter and valve; and

Fig. 4 is a bottom view of the adapter and valve.

The dominant features of the present design reside in the portions shown in full lines.

I claim:

The ornamental design for a combined garden hose adapter and relief valve, substantially as shown and described.
